UNITED STATES PATENT OFFICE.

WALTER C. REED, OF DALTON, MASSACHUSETTS, ASSIGNOR TO THE TELELECTRIC COMPANY, OF PITTSFIELD, MASSACHUSETTS, A CORPORATION OF MASSACHUSETTS.

PLAYING APPARATUS FOR MUSICAL INSTRUMENTS.

1,116,327.

Specification of Letters Patent.

Patented Nov. 3, 1914.

Application filed August 23, 1910. Serial No. 578,587.

To all whom it may concern:

Be it known that I, WALTER C. REED, a citizen of the United States, residing at Dalton, in the county of Berkshire and State 5 of Massachusetts, have invented certain new and useful Improvements in Playing Apparatus for Musical Instruments, of which the following is a specification.

This invention relates to automatic playing apparatus for pianos and other key-operated musical instruments in which the keys are struck by means of electrically-energized playing magnets, included in parallel circuits having variable resistance there- 10 in for regulating the loudness of the tones produced, and is particularly intended to provide an arrangement of variable resistances and devices for controlling the same which may be employed in connection with 15 the form of music sheet shown and described in U. S. Letters Patent No. 1,058,902, granted on the 15th day of April, 1913, for the purpose of differentiating one or more notes of a composition, with respect to their loud- 20 ness, from one or more other notes struck at the same time, or substantially so, in order to contrast the melody of the composition with the accompaniment, for example, and thus bring out the intended expression of 25 the composition as a whole. To this end, the resistances included in the playing-magnet circuits are provided respectively with one or more shunts or branch circuits, and each of these branch circuits includes a 30 sensitive or quickly-acting circuit-controlling device operated by an electro-magnet which is included in an independent circuit controlled by a special perforation or series of perforations in the music sheet, the ar- 35 arrangement being such that when any given branch circuit is closed a certain portion of the corresponding resistance is short-circuited, so that the strength of the current sent through the corresponding playing 40 magnet is increased accordingly. This ar- 45 rangement may be and preferably is em- 50 ployed in connection with sliding contact fingers such as have heretofore been em- 55 ployed for varying the resistances in the playing-magnet circuits, this being desirable for the reason that the sliding contact fingers can be operated to vary the resistance to any desired extent and thus secure slight variations in the loudness of the tones pro- 60 duced, while a resistance-varying arrange- 65

ment having the branch circuits above referred to is more particularly useful for obtaining considerable variations in the loudness of the tones and is therefore well adapted for accenting melody notes or other particular notes of a composition. It may be utilized, however, for regulating the loudness of the notes generally, whether the sliding contact fingers are employed or not. 60

In order that a considerable variety of resistance effects may be produced, each of the resistances is preferably provided with two or more branch circuits arranged to throw different amounts of resistance into or out of the corresponding playing-magnet cir- 70 circuit, so that by opening or closing the branch circuits, either individually or simultaneously, various combinations of the parts into which the resistances are divided may be included in the playing-magnet cir- 75 cuits and caused to vary the strength of the energizing current accordingly. The circuit-controlling devices which are included in the various branch circuits are preferably so grouped that the bass notes and the 80 treble notes may be independently regulated as to loudness by providing each group with its own operating magnet or other device, but they may be otherwise grouped and the various groups may be operated either 85 independently or simultaneously, according to the results which it is desired to secure in any given case. The sliding contact fingers above referred to may also be included in one set of the branch circuits, in which case 90 the circuits through the same are normally closed but are opened when it is desired to throw a large amount of resistance into the playing-magnet circuits and thereby subdue 95 the loudness of the tones produced. 95

In the accompanying drawings the invention is illustrated as applied to or embodied in a playing apparatus which, except as hereinafter explained, may have substantially the same construction and mode of 100 operation as the playing apparatus shown and described in U. S. Letters Patent No. 753,809, dated March 1, 1904, to Powers and Jewell, to which Letters Patent reference may be made for a full understanding of the 105 various parts and details which are included in the complete apparatus but are not specifically described herein, the present drawings being largely diagrammatic in character and illustrating only such parts of the 110

prior apparatus as are necessary for an understanding of the invention.

In these drawings: Figure 1 is a diagram showing the preferred arrangement of the electric circuits; Fig. 2 is a diagram showing certain of the electric circuits corresponding to a single playing magnet; Fig. 3 is a top plan view illustrating one form of mechanism for opening and closing the shunt circuits hereinafter described; Fig. 4 is a transverse section on the line 4—4 in Fig. 3; Fig. 5 is a longitudinal section through the contact cylinder shown in Fig. 3 and hereinafter described; Fig. 6 is a diagram similar to Fig. 2, but illustrating another form of circuit-controlling mechanism; Fig. 7 is a top plan view of the circuit-controlling mechanism shown in Fig. 6; and Fig. 8 is an elevation of the parts shown in Fig. 7, as viewed from the right of said figure.

Referring particularly to Fig. 1, the parts shown therein include a metallic contact bar 2, parallel circuits 3 each extending therefrom to a common return wire 4 and including a playing magnet 5, a source of electric current such as a battery 6, to one terminal of which the common return wire 4 is connected, and a wire 7 leading from the other terminal of the battery 6 to the contact bar 2 and including a switch 8 which controls the operation of the apparatus as a whole. A circuit 3, including a playing magnet 5, is provided for each piano key which is to be operated by the apparatus, but inasmuch as these circuits and playing magnets are precisely alike only four of them are shown in Fig. 1, and of these four playing magnets, two are assumed to be connected to bass keys of the keyboard and the other two are assumed to be connected to treble keys. Each of the circuits 3 also includes a suitable contact device under the control of the perforated music sheet, whereby the several circuits are opened and closed at the contact bar 2 according to the notes to be played, the arrangement for this purpose which is shown at 9 in Fig. 2 being constructed as shown and described in the Powers and Jewell patent previously referred to. In each of the circuits 3 is also included a resistance which is divided into different portions and preferably these portions are of different lengths. The number and length of these portions may be varied as desired, but in the arrangement represented in the drawings there are three of these portions, indicated at 10, 11 and 12 respectively, and their lengths are in the ratio of 3, 4 and 2. In Fig. 1 the portions 10, 11 and 12 are shown as somewhat separated, for the sake of clearness of illustration, but this is not essential, and they are commonly arranged to form a continuous

series of equi-distant coils, as indicated in Fig. 6. From the opposite ends of each resistance portion 10 branch circuit wires *a—a* lead to a circuit-controlling device such as A, hereinafter described, and in like manner branch circuit wires *b—b* lead from the opposite ends of each resistance portion 11 to another circuit-controlling device such as B. According to the arrangement illustrated in Fig. 1 there are two similar circuit-controlling devices A and also two similar circuit-controlling devices B, one of each for the resistance portions corresponding to the bass playing-magnet circuits and one of each for the resistance portions corresponding to the treble playing-magnet circuits, each of these circuit-controlling devices being arranged to operate simultaneously on all the branch circuit wires leading from the corresponding group of resistance portions, and each circuit-controlling device is provided with an operating magnet included in an independent circuit which is controlled at the contact bar 2 by a special series of perforations in the music sheet. For example, each circuit-controlling device A has its operating magnet 13 included in a circuit comprising wires 14 and 15 leading respectively from one side of the magnet to the contact bar 2, where the circuit includes a contact device such as is employed for the playing-magnet circuits, and from the other side of the magnet to a common return wire which may be the return wire 4 but is preferably an independent wire 16 joining the wire 4 at 17. In like manner each circuit-controlling device B has its operating magnet 18 included in a circuit comprising wires 19 and 20 leading respectively from one side of the magnet to the common return wire 16 and from the other side of the magnet to the contact bar 2 through one of the contact devices already referred to. The return wires 4 and 16 are preferably provided with switches 21 and 22, whereby the circuits through the same may be opened and closed independently of each other.

Two forms of circuit-controlling device are illustrated in the drawings, the device shown at A in Fig. 1 being illustrated in detail in Figs. 3, 4 and 5. This form of device consists of a series of alternating metallic disks 23 and insulating disks 24 mounted on a rod or axis 25, the disks 23 being insulated from said rod by means of a non-conducting tube 26 surrounding the latter and from one another by means of the disks 24. The disks 24 have a slightly greater diameter than the disks 23, so that a circumferential groove is provided at the periphery of each disk 23 to receive the corresponding branch circuit wires *a—a*, and each disk 23 is provided at one point of its periphery with an insulating projection, this

being preferably accomplished by boring a hole through the series of disks 23 and 24, in such position as to cut slightly through the peripheries of the disk 23, and inserting therein an insulating bar 27, which will thus project slightly beyond the outer edges of the disks 23 and into the grooves between the disks 24. Said disks are clamped firmly together between heads 28 and 29 carried by the rod 25, and said rod is mounted to oscillate on suitable fixed bearings 30 and 31 carried by a base plate 32, Fig. 3, and is operated by means of the armature 33 of the electro-magnet 13, which armature and magnet may have the same construction as the corresponding parts of the playing magnets 5. The armature 33 is mounted to turn on the bearing 31 and is connected to the rod 25 by a pin 34 entering the armature at one end and the head 29 at its other end, and a spring 35 holds said armature in the position shown in Fig. 4 when the circuit through the magnet 13 is open, so that the energizing of the magnet will result in a partial rotation of the rod 25. One of each pair of circuit wires α — α is held in constant contact with the corresponding metallic disk 23, while the companion circuit wire tends to make contact with the same disk but is normally held out of contact therewith by the insulating bar 27, as shown in Fig. 4, thus opening the circuits through the wires α — α . When the parts are in this position the portions 10 of the corresponding resistances will evidently be included in their circuits 3 and will have their effect on the energizing current sent through such of the corresponding playing magnets 5 as are in closed circuit at that time, but whenever the circuit through the magnet 13 is closed the resulting movement of its armature 33 will instantly rotate the rod 25 and the disks thereon to a sufficient extent to carry the insulating bar 27 out from under all the circuit wires α which are controlled by said bar, whereupon the corresponding portions 10 of the resistances will be short-circuited, and the circuits through the corresponding playing magnets will have their resistance reduced accordingly in case they are closed at the contact bar.

All the circuit-controlling devices A and B are constructed and arranged to operate in the manner just described, and inasmuch as each of them controls but one of the several groups of like resistance portions, different resistance effects may be obtained by operating these devices in various ways, as, for example, by short-circuiting either group of resistance portions 10, or either group of resistance portions 11, or both groups conjointly, and the resistance effects obtained in the circuits corresponding to the treble keys may also be made to differ from the resistance effects obtained in the circuits

corresponding to the bass keys by virtue of the employment of independent circuit-controlling devices in connection with the resistance circuits corresponding to these two divisions of the keyboard.

70

In connection with the resistances included in the circuits 3 a set of contact fingers 36, one for each resistance, may also be employed, which fingers are all secured to a bar 37 provided with suitable devices (not shown) for moving it back and forth in such manner as to slide the fingers 36 along the respective resistances, in contact therewith, thereby cutting out a greater or less number of the coils of which they are composed. A somewhat similar arrangement of contact fingers has heretofore been employed for varying the loudness of all the notes struck at a given time, but according to the prior construction just referred to each resistance is connected with the corresponding playing magnet through the corresponding contact finger only, which contact finger is always in circuit with the playing magnet, while in the apparatus herein represented each resistance is directly in series with the corresponding circuit 3, and the corresponding contact finger 36 forms a part of a branch circuit through which the resistance may be short-circuited to an extent depending upon the position of the finger 36. These branch circuits are opened and closed as desired by means of one or more circuit-controlling devices C, of which two are shown in Fig. 1, one for the bass-playing magnet circuits and one for the treble playing-magnet circuits. The circuit-controlling devices C are practically identical in construction with the devices A and B already described, and their operating magnets 38 are similarly included in special circuits each consisting of a wire 39, leading from one side of the magnet to the return wire 16 and another wire 40 leading from the other side of the magnet to the contact bar 2, where the circuit is controlled by a contact device similar to those employed in the other circuits and adapted to be controlled by a special series of perforations in the music sheet. In the case of each of the circuit-controlling devices C, however, the contact fingers 36 and the circuit wires 3 are normally in contact with the corresponding metallic disks 23 when the operating magnet 38 is deenergized, as shown in Figs. 1 and 2, and the insulating bar 27 is so located that when said magnet is energized the resulting movement of its armature will bring said insulating bar under the contact fingers 36 and lift the same out of contact with the respective disks 23, thus opening the branch circuits in which these contact fingers are included and rendering the same inoperative for the time being. In such case, the energizing current has to pass through the entire length of the resistances, provided

130

that no part of the same is short-circuited at that time, and the arrangement just described thus serves for subduing the loudness of the tones produced by throwing an increased resistance into the playing magnet circuits and thus reducing the current strength accordingly.

In the diagrammatic illustration of the circuit-controlling devices C in Fig. 1, the 10 disks are represented as if viewed in the direction of their axes in order to show both the contact fingers 36 and the circuits 3, but it will be understood that the actual arrangement of said disks is the same as that 15 of the corresponding disks in the circuit-controlling devices A and B. The operating magnets for all of these circuit-controlling devices are also shown in Fig. 1 as if viewed in an axial direction and each of the circuit 20 wires *a—a* and *b—b* is represented as leading to the corresponding metallic disk in a direction which is radial to the axis of that disk, for the sake of clearness of illustration, the actual arrangement being as shown 25 in Figs. 2 and 4, in which each of said circuit wires occupies a tangential relation to the corresponding disk.

In Figs. 6, 7 and 8 is shown another form 30 of circuit-controlling device which may be employed instead of the devices A and B or either of them. In this form of device any desired number of metallic contact pins 41 are carried by an insulating support 42 mounted on a suitable base 43, and an insulating block 44 is supported from the same base and carries a series of wires one for 35 each pin 41, the free ends of these wires being normally supported on an insulating bar 46 which is carried by and moves with the 40 armature 47 of an electro-magnet 48. The natural spring of the wires 45 tends to move the metallic contact pieces 49, carried thereby, into contact with the corresponding pins 41, but such movement is resisted, so long as 45 the magnet 48 is deenergized, by means of a spring 50 which tends to press the supporting bar 46 upward and is strong enough to slightly overbalance the collective effect of the wires 45. Two of these circuit-controlling 50 devices are illustrated in Fig. 6, one for the resistance portions 10 and one for the resistance portions 11, and their magnets 48 are adapted to be included respectively in the special circuits formed by the wires 14, 55 15, and 19, 20, Fig. 1, in substitution for the magnets 13 and 18. One of each pair of circuit wires *a—a* is connected to one of the wires 45 in the circuit-controlling device for the corresponding group of resistance portions, and in like manner one of each pair of circuit wires *b—b* is connected to one of the circuit wires in the other circuit-controlling 60 device, while the companion wires *a* and *b* lead from the respective contact pins 41 to 65 the corresponding resistances through wires

such as *ab*, one of which is common to both branch circuits for each resistance, a single wire *ab* being preferably employed, in practice, instead of two wires leading to the same point of the resistance as shown in Fig. 70

1. As thus constructed, the circuits through the branch circuit wires *a—a* and *b—b* are normally open at the contact pins 41, but when the circuit through either magnet 48 is closed the energizing of the magnet 75 overcomes the over-balancing effect of the spring 50 and pulls the supporting bar 46 downward, whereupon the pieces 49 instantly make contact with the pins 41 and thus short-circuit the corresponding portions 80 of the respective resistances by closing the branch circuits around the same. When the circuit through the magnet 48 is opened, however, the supporting bar 46 is instantly raised by the spring 50 and breaks the 85 branch circuits at the contact pins 41.

The circuit-controlling device just described may be adapted for use in substitution for the circuit-controlling devices C by 90 so arranging the contact pins that the circuits through the same are normally closed instead of normally open, but are opened whenever the magnet 48 is energized.

The various circuit-controlling devices above described are so sensitive, in the sense 95 of being very quickly operated to open or close the respective circuits which they control, that they make it possible to control the action of the playing magnets in such manner as to accent or subdue any desired 100 notes of a composition by the employment of the form of music sheet shown and described in U. S. Letters Patent No. 1,058,902, previously mentioned, which operation requires that the strength of the current which 105 energizes the playing magnets shall be altered instantaneously or practically so, and the present improvements are therefore particularly well adapted for use in playing apparatus in which it is desired to secure the 110 tone-differentiation above referred to, but these circuit-controlling devices may also be used for regulating generally the loudness of the tones produced, and for that purpose they may be operated manually or by means 115 of appropriate perforations in the music sheet, and either form of device may be constructed and arranged to control any desired number of branch circuits, from one upward. Various other forms of circuit-controlling devices may also be employed, if preferred, for opening and closing the branch circuits, or any of them, without departing from my invention.

The particular forms of circuit-controlling devices hereinbefore described are not 125 separately claimed herein, being described and claimed in two divisional applications filed on the 11th day of September, 1914, Serial Nos. 861,318 and 861,319.

I claim as my invention:

1. A playing apparatus for musical instruments comprising a playing magnet, an energizing circuit therefor, and means for opening and closing said circuit, a resistance included in said circuit and provided with a plurality of short-circuiting branch circuits extending around different portions of the resistance, and means for opening and closing said branch circuits independently of each other.

2. A playing apparatus for musical instruments comprising a playing magnet, an energizing circuit therefor, and means for opening and closing said circuit, a resistance included in said circuit and divided into portions of unequal resistance effect, branch circuits each adapted to short-circuit one of said portions only, and circuit-controlling devices for opening and closing said branch circuits independently of each other.

3. A playing apparatus for musical instruments, comprising a playing magnet, an energizing circuit therefor and means for opening and closing said circuit, a resistance included in said circuit, a normally-closed branch circuit including a contact finger adapted to slide along said resistance, and a circuit-controlling device for opening and closing said branch circuit.

4. A playing apparatus for musical instruments, comprising a playing magnet, an energizing circuit therefor, and means for opening and closing said circuit, a resistance included in said circuit and provided with one or more short-circuiting branch circuits, a contact finger adapted to slide along said resistance and included in a normally-closed, independent branch circuit, and circuit-controlling devices for opening and closing said branch circuits independently of one another.

5. A playing apparatus for musical instruments, comprising playing magnets arranged in parallel circuits and means for opening and closing said circuits, resistances included in the respective playing-magnet circuits, each resistance being provided with a branch circuit adapted to short-circuit a portion only of said resistance, and independent means for progressively varying said resistances and for opening and closing said branch circuits.

6. A playing apparatus for musical instruments, comprising playing magnets arranged in parallel circuits and means for opening and closing said circuits, resistances included in the respective playing-magnet circuits and means for short-circuiting different portions of each resistance independently of each other.

7. A playing apparatus for musical instruments, comprising playing magnets arranged in parallel circuits and means for opening and closing said circuits, resistances

included in the respective playing-magnet circuits, each resistance being divided into two or more portions of unequal resistance effect, and means for short-circuiting the several portions of each resistance independently of one another.

8. A playing apparatus for musical instruments, comprising playing magnets arranged in parallel circuits and means for opening and closing said circuits, resistances included in the respective playing-magnet circuits and each provided with a plurality of branch circuits each of which is adapted when closed to short-circuit that portion of the resistance around which it leads, said branch circuits being arranged in groups, and means for opening and closing simultaneously all the branch circuits in each group independently of those in the other group or groups.

9. A playing apparatus for musical instruments, comprising playing magnets arranged in parallel circuits and means for opening and closing said circuits, resistances included in the respective playing-magnet circuits and each provided with a plurality of branch circuits each of which is adapted to short-circuit a portion only of the corresponding resistance, the branch circuits corresponding to the treble playing-magnet resistances and those corresponding to the bass playing-magnet resistances being arranged in independent groups, and means for opening and closing simultaneously all the branch circuits in each group.

10. A playing apparatus for musical instruments, comprising playing magnets arranged in parallel circuits and means adapted to be operated by a perforated music sheet for opening and closing said circuits, resistances included in the respective playing-magnet circuits and each provided with a plurality of branch circuits each of which is adapted to short-circuit a portion only of the corresponding resistance, circuit-controlling devices each arranged to open and close simultaneously a plurality of corresponding branch circuits, and means controlled by special perforations in the music sheet for operating said circuit-controlling devices.

11. A playing apparatus for musical instruments, comprising playing magnets arranged in parallel circuits and means adapted to be operated by a perforated music sheet for opening and closing said circuits, resistances included in the respective playing-magnet circuits and each provided with a branch circuit adapted to short-circuit a portion only of the corresponding resistance, circuit-controlling devices each arranged to open and close simultaneously a plurality of said branch circuits, each circuit-controlling device being provided with an electro-magnet for operating the same, and special circuits including the latter magnets respec-

tively and adapted to be controlled by the music sheet independently of one another.

12. A playing apparatus for musical instruments, comprising playing magnets arranged in parallel circuits and means adapted to be operated by a perforated music sheet for opening and closing said circuits, resistances included in the respective playing-magnet circuits and each provided with a plurality of branch circuits each adapted to short-circuit a portion of the corresponding resistance, the branch circuits around corresponding resistance portions being arranged in groups, and means for independently opening and closing the groups of branch circuits comprising circuit-controlling devices, one for each group, an electro-magnet for operating each circuit-controlling device, and special circuits each including one of said magnets and adapted to be controlled by the music sheet independently of one another.

13. A playing apparatus for musical instruments, comprising playing magnets arranged in parallel circuits and means for opening and closing said circuits, resistances included in the respective playing-magnet circuits, sliding contact fingers arranged to be moved along the respective resistances and included in normally closed branch circuits around the same, and means for opening and closing the branch circuits through said contact fingers.

14. A playing apparatus for musical instruments, comprising playing magnets arranged in parallel circuits and means for opening and closing said circuits, resistances included in the respective playing-magnet circuits and each provided with a branch circuit adapted to short-circuit a portion only of the corresponding resistance, means for opening and closing a plurality of said branch circuits simultaneously, contact fingers movable along the respective resistance and included in normally-closed branch circuits around the same, and means for opening and closing the branch circuits through said contact fingers.

15. A playing apparatus for musical instruments, comprising playing magnets arranged in parallel circuits and means for opening and closing said circuits, resistances included in the respective playing-magnet circuits and each provided with one or more short-circuiting branch circuits, means for opening and closing said branch circuits, other branch circuits associated with the respective resistances and including sliding contact fingers adapted to be moved along said resistances, and means for opening and closing the branch circuits through said contact fingers.

16. A playing apparatus for musical instruments, comprising playing magnets arranged in parallel circuits and means adapt-

ed to be operated by a perforated music sheet for opening and closing said circuits, resistances included in the respective playing-magnet circuits and each provided with one or more short-circuiting branch circuits, 70 said branch circuits being arranged in groups, sliding contact fingers arranged to be moved along the respective resistances and included in branch circuits leading around the same, the latter branch circuits 75 being also arranged in groups, independently-operable circuit-controlling devices for opening and closing corresponding groups of branch circuits, and means controlled by special perforations in the music sheet for 80 operating said circuit-controlling devices.

17. A playing apparatus for musical instruments, comprising playing magnets arranged in parallel circuits, means for opening and closing said circuits, resistances included in the respective playing-magnet circuits, each resistance being provided with a short-circuiting branch circuit, and means for controlling said branch circuits comprising a series of insulated metallic disks 90 mounted on a common shaft, each disk being provided on its periphery with an insulating portion, circuit wires arranged in pairs with the wires of each pair held in contact with one of said disks, and means for partially 95 rotating said shaft to move the insulating portions on the disks into and out of contact with the adjacent circuit wires.

18. A playing apparatus for musical instruments, comprising playing magnets arranged in parallel circuits, means for opening and closing said circuits, resistances included in the respective playing-magnet circuits, each resistance being provided with a short-circuiting branch circuit, and means for 100 controlling said branch circuits comprising a series of insulated metallic disks mounted on a common shaft, each disk being provided on its periphery with an insulating portion, circuit wires arranged in pairs with the 105 wires of each pair held in contact with one of said disks, and means comprising an electro-magnet and an oscillating armature connected to said shaft for partially rotating the latter to move the insulating portions on the 110 disks into and out of contact with the adjacent circuit wires.

19. A playing apparatus for musical instruments, comprising playing magnets arranged in parallel circuits, means for opening and closing said circuits, resistances included in the respective playing-magnet circuits, each resistance being provided with a short-circuiting branch circuit, and means for controlling said branch circuits comprising a series of insulated metallic disks 120 mounted on a common shaft, an insulating rod passing through said series of disks and exposed at one point of the periphery of each disk, a pair of circuit wires bearing against 125

the periphery of each disk, and means for oscillating said shaft to move the insulating rod into and out of contact with the adjacent circuit wires.

- 5 20. A playing apparatus for musical instruments, comprising playing magnets arranged in parallel circuits, means for opening and closing said circuits, resistances included in the respective playing-magnet circuits, each resistance being provided with a short-circuiting branch circuit, and means for controlling said branch circuits comprising a series of metallic disks and a series of insulating disks arranged in alternation and 10 mounted on a common shaft, the insulating disk being of greater diameter than the metallic disks to provide annular spaces at the

periphery of the latter disks and each metallic disk being provided at one point on its periphery with an insulating portion, a pair 20 of circuit wires located in each annular recess in contact with the corresponding metallic disk, and means for oscillating said shaft to move the insulating portions into and out of contact with the adjacent circuit 25 wires.

In testimony whereof, I have hereunto subscribed my name this 19th day of August, 1910.
